R. M. JONES.

POLE, PILE, AND COLUMN OF REINFORCED CONCRETE.

APPLICATION FILED JAN. 16, 1912.

UNITED STATES PATENT OFFICE.

ROBERT M. JONES, OF DENVER, COLORADO.

POLE, PILE, AND COLUMN OF REINFORCED CONCRETE.

1,065,529.

Specification of Letters Patent. Patented June 24, 1913.

Application filed January 16, 1912. Serial No. 671,533.

To all whom it may concern:

Be it known that I, ROBERT M. JONES, a citizen of the United States, residing at Denver, in the county of Denver and State of Colorado, have invented certain new and useful Improvements in Poles, Piles, and Columns of Reinforced Concrete, of which the following is a specification.

My invention relates to poles, piles and columns of reinforced concrete, and its object resides in the provision of a simple method of construction which briefly, consists in producing articles of the above mentioned character, in two or more complementary sections, which when united, form a structure which excels in strength and durability.

An embodiment of my invention is shown in the accompanying drawings in the various views of which like parts are similarly designated and in which,

Figure 1 represents a fragmentary view, partially in section, of a pole, pile or column of the character described formed of two sections, Fig. 2, a transverse section taken along the line 2—2, Fig. 1, Fig. 3, a fragmentary elevation of one of the sections of which the structure shown in Fig. 1 is composed, Fig. 4, a fragmentary elevation of the pole, pile or column partially surrounded by the casing or jacket which, in the practice of my process, is employed to temporarily maintain the adjoining sections of the structure in their relative positions, and Fig. 5, a cross-section taken along the line 5—5, Fig. 4.

Referring more specifically to the drawings, the letters A and B designate respectively the two sections of which the article shown in Fig. 1 is composed. Each of these sections consists of a hollow cylinder made of concrete and reinforced by metallic rods C which extend longitudinally through its wall. These reinforcing rods project beyond the end of each section at which in the construction of the pole or column it is to adjoin a complementary section, and the protruding end portions of the rods are divided into two distinctive groups which in the drawings are respectively designated by the letters E and D. The portions of the rods C comprised in the group designated by the letter E extend in alinement with their body portions which are embedded in the wall of the section, and they serve in the

process of joining the sections, to determine the distance between the adjacent ends thereof and temporarily support the one upon the other. The rod-portions D comprised in the other group are of a length 60 greatly exceeding that of the portions E and they are bent from the points at which they protrude beyond the end of the section, inwardly toward the longitudinal axis of the same to freely enter the interior of the adjoining section when the parts are being placed in their relative positions.

The sections used in the construction of poles are preferably provided with a series of metal-lined openings H for the insertion 70 of steps by means of which the pole may be climbed to reach the electric conductors or other parts supported at the upper end thereof, and the lower one of each two adjoining sections is furthermore provided at 75 the time it is made, with a transverse partition F which in the process of joining the two sections serves as a stop and support for the plastic material by the use of which the joint is produced.

The process of joining two of the above described sections is carried out as follows: After the lower section, B, has been rigidly secured in place upon a suitable foundation, the upper section A, after having been suspended in axial alinement therewith, is lowered until the ends of the rod-portions E of each section engage the end-surface of the other section. While the upper section is being placed in its proper position with relation to the lower one, the group of rod portions D of each of the two sections, will enter the interior of the adjoining one, the rods comprised in the two groups, intersecting one another in the space between the separated ends of the sections. The upper section is now secured in its position relative to the lower one, by means of a casing or jacket I shown in Figs. 4 and 5 of the drawings, which being firmly clamped around the 100 adjoining end-portions of the two sections, incloses the open space between the opposite ends thereof which as stated above are separated from each other by the protruding portions of the reinforcing rods comprised 105 in the groups. This casing consists of two overlapping component parts made of sheet metal, which are securely clamped around the sections to be joined by means of surrounding bands J, the threaded extremities 110

of which are drawn through passages in shoes K, by means of nuts applied thereto. After the parts are thus connected, concrete or other suitable plastic material G is poured into the upper end of the upper section A, onto the partition F in the lower section, until its level has reached the upper ends of the rods D which extend within the upper section, this plastic mass is agitated until it fills every part of the interior of the two sections and the space between the same, and is then permitted to dry and harden after which the jacket I is removed. In case the height of the pole or column renders the introduction of the plastic filling G into the upper end thereof, impracticable, the upper section may be provided with one or more ports L as shown in Fig. 4, through which the material is introduced into the interior of the structure. Before the jacket I is put in place and the plastic filling is poured into the connected sections, the lined openings H for the pole-steps within the portions of the structure to be occupied by the filling G, are plugged with a mixture of sand and cement, which after the filling has solidified, may be readily removed by chipping. A pole, pile or column of considerable length may thus be readily built up of separate sections which greatly facilitate its erection and transportation and the structure when completed will be as strong, if not stronger than if it had been originally made in one piece.

While the sections of which the pole or column is composed have been shown in the drawings as being cylindrical in form, they are in practice, made preferably of conoidal

form to collectively produce a tapering structure.

Having thus described my invention what I claim is:

1. A pole, pile or column of plastic material comprising axially aligned, hollow sections, spaced from each other, rods embedded in the wall of one section and projecting beyond an end thereof, the protruding portions of said rods being divided into two groups, those comprised in one engaging the end-surface of the adjacent section whereby to maintain them at a determinate distance from each other, and those in the other group extending within said adjacent section, and a filler of plastic material occupying said space and adjoining end portions of said sections. 40

2. A pole, pile or column of plastic material comprising axially aligned, hollow sections, spaced from each other, rods embedded in the wall of each section and projecting beyond an end thereof, the protruding portions of said rods being divided into two groups, those comprised in one engaging the end-surface of the adjacent section whereby to maintain them at a determinate 45 distance from each other and those in the other group extending within the hollow of the said adjacent section, and a filler of plastic material occupying said space and adjoining end portions of said sections. 50

In testimony whereof I have affixed my signature in presence of two witnesses.

ROBERT M. JONES.
